UNITED STATES PATENT OFFICE.

BARNIE B. MCENTIRE, OF IRMO, SOUTH CAROLINA.

LOCOMOTIVE REVERSING DEVICE.

1,248,357.

Specification of Letters Patent. Patented Nov. 27, 1917.

Application filed February 8, 1916. Serial No. 77,043.

To all whom it may concern:

Be it known that I, BARNIE B. MCENTIRE, a citizen of the United States, residing at Irmo, in the county of Lexington and State 5 of South Carolina, have invented new and useful Improvements in Locomotive Reversing Devices, of which the following is a specification.

This invention relates to locomotive reversing devices, and it has for its object to produce a simple and thoroughly effective device whereby the link motion may be mechanically actuated.

A further object of the invention is to produce a simple and improved device of the character described wherein the shifting lever may be operated by a steam actuated piston, such steam actuated piston serving also to actuate the piston in a cylinder containing water or other liquid, the same serving as a dash pot to prevent or reduce sudden shocks and to take up lost motion.

A further object of the invention is to simplify and improve the construction and arrangement of parts constituting the improved device.

With these and other ends in view which will readily appear as the nature of the invention is better understood, the same consists in the improved construction and novel arrangement and combination of parts which will be hereinafter fully described and particularly pointed out in the claim.

In the accompanying drawings has been illustrated a simple and preferred form of the invention, it being, however, understood that no limitation is necessarily made to the precise structural details therein exhibited, but that changes, alterations and modifications within the scope of the claim may be resorted to when desired.

In the drawings,—

Figure 1 is a view in side elevation showing a device constructed in accordance with the invention and showing also, in section, a platform or supporting member for the said device and a portion of the locomotive boiler below which the platform is arranged.

Fig. 2 is a sectional plan view taken on 50 the line 2—2 in Fig. 1.

Fig. 3 is a longitudinal vertical sectional view taken on the line 3—3 in Fig. 2.

Fig. 4 is a transverse sectional view taken on the line 4—4 in Fig. 2.

Fig. 5 is a sectional detail view taken on 55 the line 5—5 in Fig. 4.

Fig. 6 is a sectional view taken on the line 6—6 in Fig. 3.

Fig. 7 is a sectional detail view taken on 60 the line 7—7 in Fig. 2.

Fig. 8 is a sectional detail view taken on the line 8—8 in Fig. 2.

Fig. 9 is a sectional detail view of the valve 44.

Corresponding parts in the several figures 65 are denoted by like characters of reference.

The steam cylinder 15 has a valve chest 16 in which operates a rocking valve 17 having a steam chamber 18 normally communicating with the steam intake 19 to which live 70 steam is supplied through a pipe 20. The valve 17 has a port 21 which may be alternately placed in communication with the ducts or passages 22 leading to opposite ends of the cylinder, or said port may occupy a 75 neutral position, as seen in Fig. 3. The valve 17 also has a chamber 23 communicating with the exhaust pipe 24, the walls of said chamber being provided with ports 25 which may be alternately placed in communication with the two ends of the cylinder through the ducts or passages 22, it being understood that when the valve is rocked from its neutral position one end of the cylinder will be placed in communication 85 with the steam intake and the other with the exhaust. The valve for the purpose of rocking the same is provided with a crank 26 which is connected by a rod 27 with a controlling lever 28 which is located in a high 90 position conveniently accessible to the engineer. The said lever may be arranged in any well known manner to be operated either manually or by the foot of the operator. An oil cup 29 supplies lubricant to the valve 17. 95

A second cylinder 30 which is of substantially the same length as the cylinder 15, but which is preferably of a larger cross sectional area, is located in axial alinement therewith, said second cylinder containing a 100 piston 31. A rod or stem 32 which carries the piston 31 extends through both heads or ends of the cylinder 30 and also through one head of the cylinder 15 within which it carries the piston 33, the latter thus operating 105 in unison with the piston 31 so that when the piston 33 is forced from one end of the cylinder 15 to the other end the piston 31

will be moved correspondingly in the cylinder 30. The cylinder 30 supports a water tank 36 which is in communication with the exhaust pipe 24 through a branch 37 having a check valve 38 and a strainer 39, the tank 36 serving as a condensing tank. The tank 36 is connected with the two ends of the cylinder 30 by means of pipes 40, each having a check valve 41, the cylinder 30 being thus supplied with water to its full capacity. Air cocks 42 are mounted in the ends or heads of the cylinder 30 to provide for the escape of air contained in the cylinder to the atmosphere when the cylinder is being filled with water. The two ends of the cylinder 30 are placed in communication with each other through the medium of a pipe 43 having a valve 44, the stem of which is provided with a crank 45, see Fig. 2, whereby the valve may be actuated. The valve when in a neutral position, as seen in Fig. 2, will obstruct communication between the ends of the cylinder 30, but communication will be opened when the valve is rocked in either direction. The crank 45 is connected by a rod 46 with the crank 26 of the valve 17, thus causing the said valves 17 and 44 to be operated in unison.

The piston rod 32 has an extension member 47 which is adjustably connected therewith by a sleeve 48 engaging right and left threaded portions of the members 32 and 47, as best seen in Fig. 1, the extension member 47 being connected by a pitman 49 with the shifting lever 50 of the link motion which, as a whole, is designated by L. The shifting lever 50 is connected by a rod 51 with an indicator 52 pivotally mounted on a dial 53 and serving to indicate the position of the link motion whether the latter be adjusted to "forward" or to "reverse."

The piston rod 32 is guided in adjustable bearings 54 and on the piston between said bearings is mounted a sleeve 55 having a radially extending arm 56 with which is connected one end of a rod 57 having a turn buckle 58, whereby the length thereof may be adjusted, said rod having a terminal slot 59 which embraces the crank 45 of the valve 44. The slot 59 is of a length approximately equal to the stroke of the piston rod so that in either extreme position of the piston rod one end wall of the slot 59 will engage the crank 45, permitting said crank to be moved in the direction of the opposite end wall of the slot when actuated, together with the valve 17, by means of the lever 28 and related parts. When the valves 44 and 17 are thus actuated the piston rod, under the influence of the steam entering the cylinder 15 will be moved longitudinally, causing the piston 31 to displace the water in front thereof as it advances, the water traveling through the pipe 43 having the valve 44 to the other end of the cylinder. By

the movement of the piston rod and the rod 57 connected therewith and having the slot 59 engaging the valve stem 45, the valve 44 will be restored to its neutral or closed position when the link block reaches the limit of its movement, the valve 17 being likewise restored to neutral position owing to the connection of the crank 26 with the crank 45 of the valve 44. Should adjustment of the valves be required while the link block is between the extreme limits of its movement, such adjustment must obviously be performed by a proper manipulation of the hand lever 28. It will be seen, however, that when adjustment of the link block is required terminating at the extreme limit of its movement, the closure of the valves 24 and 17 will be performed automatically. The lever 28 will also be restored to a neutral position; hence the necessity for providing the indicator 52 and dial 53, a glance at which will reveal to the engineer the present position of the link motion.

An extension 60 of the live steam pipe 20, said extension having a valve 61, is connected with the tank 36 in order that in extremely cold weather the water contained in said tank may be kept from freezing.

From the foregoing description, taken in connection with the drawings hereto annexed, it will be seen that a simple and effective means has been provided whereby the link motion of a locomotive may be mechanically actuated, thus not only relieving the engineer from the severe strain often required to effect the shifting of the link motion, but also avoiding the possibility of injury to the operator as now frequently happens. The improved device is simple in construction, and it may be readily installed on switching and other engines.

Having thus described the invention, what is claimed as new, is:—

A device for actuating the shifting lever of a link motion, said device comprising a steam cylinder, a piston operating therein, a water cylinder, a stem connected with the piston of the steam cylinder and extending through one end of the latter and through the two ends of the water cylinder, a piston carried on the stem within the water cylinder, a pipe establishing communication between the two ends of the water cylinder, a valve in said pipe having an operating crank, a valve controlling admission of live steam to the steam cylinder, said valve having an operating crank, a connection between the cranks of the two valves whereby they may be simultaneously operated, an operating lever connected with the crank of the steam valve, and a member operatively connecting the piston stem with the shifting lever of a link motion, in combination with a sleeve mounted on the piston rod and having a radial arm and a rod connected with

said arm in parallel relation to the piston rod and having a slot embracing the crank of the water valve whereby said water valve and related parts including the steam valve 5 may be manually adjusted when the link block is in an intermediate position and will be restored to neutral position after being actuated by the operating lever when the

link block reaches the limit of its movement in either direction.

In testimony whereof I affix my signature in presence of two witnesses.

BARNIE B. McENTIRE.
